DESIGN FOR A DOLL OR SIMILAR ARTICLE

Gretchen v. B. Menken, New York, N. Y.

Application July 22, 1938, Serial No. 78,643

Term of patents 3½ years

To all whom it may concern:

Be it known that I, Gretchen v. B. Menken, a citizen of the United States of America, residing at the Hotel Ambassador, 51st Street and Park Avenue, in the Borough of Manhattan, city, county, and State of New York, have invented a new, original, and ornamental Design for a Doll or Similar Article, of which the following is a specification, reference being had to the accompanying drawing, forming a part thereof, and showing in Fig. 1 a front view of the doll, while Fig. 2 shows a rear view thereof.

In the drawing the markings on the skirt and sleeves are such as appear on architectural blue-prints.

I claim:

The ornamental design for a doll or similar article, substantially as shown and described.

GRETCHEN v. B. MENKEN.
